METHOD OF PREPARATION OF ACETALDEHYDE.

1,315,543.

Specification of Letters Patent.

Patented Sept. 9, 1919.

Application filed June 3, 1916, Serial No. 101,638. Renewed December 12, 1917. Serial No. 906,849.

To all whom it may concern:

Be it known that I, GEORGE O. CURME, Jr., a citizen of the United States, residing at Pittsburgh, Allegheny county, and State of Pennsylvania, have invented and discovered certain new and useful Improvements in Methods of Preparation of Acetaldehyde, of which the following is a specification.

Ethylene and a salt of mercury react in aqueous solution to form a compound of the type $HgSO_4 \cdot C_2H_4$, such as is formed by the inter-action of mercuric sulfate and ethylene in aqueous solution; these compounds being readily soluble in water and acting so as to yield up the ethylene content readily, offer the possibility of obtaining a considerable concentration of ethylene in the aqueous solution. The ethylene portion of the compounds above specified is capable of oxidation and, by suitable means, can be transformed into acetaldehyde.

My present invention, therefore, consists in the method and means for preparing acetaldehyde by the anodic oxidation of ethylene in an electrolytic cell in the presence of a salt of mercury.

The accompanying drawing illustrates an apparatus which is found suitable for the purpose. Said apparatus consists of a cell 30 formed with double walls between which is mounted a heating coil 11. Within the cell is mounted a ring-shaped anode 12 and a cone-shaped diaphragm 13 dividing the cell into an anode chamber above said diaphragm and a cathode chamber below said diaphragm. Said diaphragm terminates at the top in a discharge tube or central outlet 14 for the hydrogen formed simultaneously in the process of electrolysis. An inlet pipe 40 15 connects with a perforated ring 16 mounted beneath the anode and above the cathode in the cell, and an outlet pipe 17 leads out from the top of the cell for the discharge of acetaldehyde vapors mixed with ethylene 45 leading to condenser, not shown, where acetaldehyde is removed.

It will be understood, of course, that the apparatus thus illustrated is merely a suggested arrangement, found suitable for the purpose, but may be modified materially as may be desired for varying commercial uses. The cone diaphragm 13 is of porous material pervious to liquids but not to gases when wet, and separates the cathode cham-

ber from the anode chamber, and both chambers are filled with solutions described below.

The anode may be of platinum, lead peroxid, magnetite, or other suitable substance such as will not be attacked either by the acid solution or by the oxidizing influence of the anode chamber, and the chamber containing the same is charged with aqueous sulfuric acid from 0-50% concentration and the desired amount of mercuric sulfate, or compound of mercury forming the sulfate when in contact with the acid of the strength given. This amount may vary from the smallest to a considerable quantity greater than what will dissolve in the acid of the strength given. The cathode in the cathode chamber, separated from the anode chamber by the porous funnel-shaped diaphragm, may be of mercury, or other suitable material to withstand the acid solution, and is also submerged in a bath of sulfuric acid of the same strength as used in the other chamber.

After the cell is thus prepared, ethylene is introduced into the anode chamber, 80 through the pipe 15 and perforations in ring 16 connected to the lower end thereof, and bubbles through the mercury salt-sulfuric acid solution, or, in other manner, is brought into intimate contact with it, and 85 the electric current is allowed to pass. The ethylene reacts with the mercury salt, the resulting compound is thus dissolved and subjected to the oxidizing influence of the anode, where it is oxidized to acetaldehyde, 90 regenerating the mercury salt in its original condition at the same time.

In this process, the solution is kept at a temperature between 21° C., the boiling point of acetaldehyde, and the boiling point of the solution used, under which conditions the acetaldehyde is volatilized and can be removed from the anode chamber as rapidly as formed. In good practice the amount being further oxidized to acetic acid may 100 be kept very small indeed. By a suitable condensing device (not shown), the acetaldehyde is condensed out as rapidly as formed, while the ethylene, which may escape with the acetaldehyde vapors, is returned to the anode chamber for further treatment.

Stirring favors the reaction.

The presence of a certain salt in the anode chamber acts catalytically in favoring the oxidizing reaction.

The current density on the anode may 5 vary between wide limits. Current densities up to 5.0 amperes per square decimeter will give good results and even higher densities may profitably be used. The voltage required is that necessary to produce the desired current in any given cell 10 where the resistance is approximately constant. It need not exceed 4.0 volts in most cases.

Having thus fully described my said 15 invention, what I claim as new and desire to secure by Letters Patent, is:

1. The process of forming acetaldehyde which consists in combining ethylene with a mercury salt solution, subjecting the compound thus formed to anodic oxidation in 20 aqueous solution, and removing the acetaldehyde by continuous distillation, substantially as set forth.

2. The process of forming acetaldehyde which consists in combining ethylene with 25 a mercury salt solution in an electrolytic cell, subjecting the compound thus formed to anodic oxidation, removing the acetaldehyde by volatilization, and condensing the same in a separate chamber, substantially as set forth.

3. The process of forming acetaldehyde which consists in combining ethylene with a mercury salt solution charged with 35 aqueous sulfuric acid from 0-50% concentration, subjecting the compound thus formed to anodic oxidation, and removing the acetaldehyde by distillation, substantially as set forth.

40 4. The process of forming acetaldehyde which consists in combining ethylene with a mercury salt solution at a temperature maintained at a point above the boiling point of acetaldehyde, subjecting the compound thus formed to anodic oxidation, and

removing the acetaldehyde by distillation, substantially as set forth.

5. The process of forming acetaldehyde which consists in combining ethylene with a mercury salt solution in an electrolytic 50 cell, subjecting the compound thus formed to anodic oxidation, the anode being composed of platinum, lead peroxid, magnetite, or similar substance, and removing the acetaldehyde by distillation, substantially as 55 set forth.

6. The process of forming acetaldehyde which consists in combining ethylene with a mercury salt solution, subjecting the compound thus formed to anodic oxidation in 60 an electrolytic cell wherein the anode chamber and the cathode chamber are separated by a porous diaphragm, the cathode consisting of mercury or other suitable material, and removing the acetaldehyde by distillation, substantially as set forth.

7. The process of forming acetaldehyde which consists in combining ethylene with a mercury salt in the presence of a cerium salt in an anodic chamber of an electrolytic 70 cell, subjecting the compound thus formed to anodic oxidation, and removing the acetaldehyde by distillation, substantially as set forth.

8. The process of forming acetaldehyde 75 which consists in combining ethylene with a mercury salt solution in an electrolytic cell, passing an electric current through the cell of the proper density and voltage, thus subjecting the compound to anodic oxidation, 80 and removing the acetaldehyde by distillation, substantially as set forth.

In witness whereof, I have hereunto set my hand and seal at Washington, District of Columbia, this twenty-ninth day of May, 85 A. D. nineteen hundred and sixteen.

GEORGE O. CURME, JR. [L. S.]
